DESIGN FOR A REFRIGERATOR BOX OR SIMILAR ARTICLE

Herman Zaikaner, New York, N. Y.

Application June 10, 1948, Serial No. 146,868

Term of patent 14 years

(Cl. D44—1)

To all whom it may concern:

Be it known that I, Herman Zaikaner, a citizen of the United States and residing at New York, in the county of New York and State of New York, have invented a new, original, and ornamental Design for Refrigerator Box or Similar Article, of which the following is a specification, reference being had to the accompanying drawing, forming part thereof, and in which

Fig. 1 is a perspective view showing my new design for a refrigerator box or similar article,

Fig. 2 is a like view of the inverted box, and

Fig. 3 is an end elevation thereof on a somewhat larger scale.

I claim:

The ornamental design for a refrigerator box or similar article, substantially as shown.

HERMAN ZAIKANER.
